INVENTOR

BY Victor J. Evans

ATTORNEY

Paul M. Hunter

WITNESS:

UNITED STATES PATENT OFFICE.

HARRY V. CROSLEY, OF ROUNDUP, MONTANA.

TRACTION-INCREASING MEANS FOR TRACTION ENGINES.

Application filed August 13, 1923. Serial No. 657,074.

To all whom it may concern:

Be it known that I, HARRY V. CROSLEY, a citizen of the United States, residing at Roundup, in the county of Musselshell and 5 State of Montana, have invented new and useful Improvements in Traction-Increasing Means for Traction Engines, of which the following is a specification.

The object of my said invention is the 10 provision of traction increasing means susceptible of being readily applied to and removed from traction engine wheels, and this in such manner that the wheels are not weakened appreciably, and the pressure applied to the traction increasing means will not tend to loosen the connection between 15 said means and the wheels; the said connection being of such a character that the traction increasing means can be put on or removed without raising the engine.

The laws of many States inhibit the passage of traction engines over bridges and paved highways unless the traction increasing means of such engines are removed, and 20 hence the ready removal of traction increasing is a desideratum.

To the attainment of the foregoing, the invention consists in the improvement as 25 hereinafter described and definitely claimed.

30 In the accompanying drawings, forming part of this specification:—

Figure 1 is a general view of a section of 35 traction increasing means constructed in accordance with my invention.

Figure 2 is an edge elevation of the same.

Figure 3 is a plan view showing the inner side of said section.

Figure 4 is an enlarged detail plan showing 40 the outer side of a portion of the section and one lug carried thereby.

Figure 5 is an enlarged detail longitudinal section taken in the plane indicated by the line 5—5 of Figure 4 and showing the 45 relative arrangement of one lug and one carrying strap, and the manner of connecting the lug to the strap and bracing the lug by the strap.

Figure 6 is a general view of a modification 50 that is resorted to when the width of a wheel requires two rows of lugs.

Figure 7 is a detail longitudinal section on the line 7—7 of Figure 6.

Figure 8 is a detail enlarged cross-section 55 on the line 8—8 of Figure 6, and showing the manner in which each lug of the modi-

fied construction is connected to two carrying straps.

Similar numerals designate corresponding parts in Figures 1 to 5 to which reference will first be made.

I would have it understood that my novel traction increasing means comprises several arcuate sections such as shown in Figures 1, 2 and 3, the said sections being arranged end to end around the peripheral portion of 65 a traction wheel and being connected at their ends to said peripheral portion by means of bolts or other appropriate fastening devices. The said sections are identical in construction and therefore a detailed description of the one shown in Figures 1 to 70 3 will suffice to impart a definite understanding of all. The said section includes two arcuate carrying straps 1 of appropriate metal arranged in parallelism and having by 75 preference apertures 2 adjacent to their ends for the passage of connecting bolts. The section also comprises spaced traction affording lugs 3 which are also formed of appropriate metal and are spaced apart and are arranged by preference at acute angles 80 to the carrying straps 1. The said lugs 3 are of right angle form in cross section, and each includes a base portion 5 arranged against the inner sides of the straps 1 and an outwardly extending portion 6 apertured 85 at 7 and snugly receiving the straps 1; the base portion being fixedly connected to the carrying straps 1 by rivets 8 or other appropriate means. By virtue of the said construction and relative arrangement of straps and lugs it will be manifest that each lug of 90 itself is in a measure connected to and held on the carrying straps with the result that the major portion of the strain incident to the use of the traction increasing means 95 is taken off the rivets 8 or other connecting means.

It will be manifest from the foregoing that each of the sections described includes 100 a number of lugs 3, and from this it follows that the traction increasing means complementary to a traction wheel may be expeditiously and easily applied to and readily disconnected from the wheel.

The modification shown in Figures 6, 7 and 8 is designed for use on comparatively wide wheels, and is made up of three straps 1^a similar to the straps 1, and two rows of lugs 3^a, similar to the lugs 3, and connected 110

to and relatively arranged on the straps 1^a in the same manner that the lugs 3 are arranged on and connected to the straps 1. It will be observed however, that in the 5 modified construction the lugs 3^a of one row alternate with the lugs 3^a of the other row; also, that the inner portions of the lugs of the two rows are arranged in lapped though spaced relation, and that the lugs 10 of the two rows are so disposed that the lugs of one row extend at an angle with the lugs of the other row so that each pair of adjacent lugs in the two rows form substantially obtuse angles. Manifestly this 15 construction affords great traction to a wide wheel.

Like the embodiment shown in Figures 1 to 5, the embodiment shown in Figures 6 to 8 is susceptible of being readily applied to 20 and removed from a traction wheel for the reasons hereinbefore indicated.

I have entered into a detailed description of the construction and relative arrangement of the parts embraced in the 25 present and preferred embodiments of my invention in order to impart a full, clear and exact understanding of the said embodiments. In do not desire, however, to be understood as confining myself to the specific construction and relative arrangement 30 of parts inasmuch as in the future practice of the invention various changes and modifications may be made such as fall within the scope of my invention as defined in my 35 appended claims.

Having described my invention, what I claim and desire to secure by Letters-Patent, is:—

1. In traction increasing means for traction 40 wheels, an arcuate carrying strap in combination with a lug carried by and intersecting the strap, the said lug being of angular cross section and having a base

portion attached to the strap and also having an upwardly extending portion with an 45 aperture snugly receiving the strap.

2. In traction increasing means for traction wheels, arcuate carrying straps arranged in parallelism, and spaced lugs arranged on and at an angle to the straps; 50 the said lugs being of angular cross-section and each having a base portion arranged at the inner sides of and connected to the straps and also having an outwardly extending portion with apertures snugly receiving 55 the straps.

3. Traction increasing means for traction wheels comprising spaced arcuate carrying straps in parallelism, and spaced lugs carried by and on the straps and disposed at acute angles to the straps; each of the lugs including a base portion arranged at the inner sides of and connected to the straps and an outwardly extending portion disposed substantially at right angles 65 to the base portion and having in its inner portion apertures snugly receiving the straps whereby the lug is held of itself on the straps.

4. Traction increasing means for traction 70 wheels comprising three arcuate spaced straps in parallelism, and two rows of lugs carried by and on the straps; the lugs being of angular form in cross-section and the lugs of each row intersecting the intermediate strap and one of the outer straps, and the lugs of the two rows being disposed at obtuse angles to each other, and each lug having an inner portion arranged 75 at the inner side of two straps and connected thereto, and an outer portion with apertures snugly receiving the straps.

In testimony whereof I affix my signature.

HARRY V. CROSLEY.
